UNITED STATES PATENT OFFICE.

HECTOR F. PATENAUME, OF BISBEE, ARIZONA.

ATTACHMENT FOR HAIR CLIPPERS.

Application filed March 30, 1926. Serial No. 98,488.

The present invention relates to an attachment for hair clippers particularly designed for use on electro-magnetically operated hair clippers.

5 An important object of the invention is to provide an attachment of this nature which permits the barber to clip the hair with the magnetically operated hair clippers without the necessity of finishing up with hand operated hair clippers.

At the present time, it is customary for a barber to use the electro-magnetically operated hair clippers for the major portion of the hair cut and to finish up with hand 15 clippers. My attachment is formed in such a manner that the barber is able to rock the electro-magnetically driven hair clippers to place the same at various angles to the head for cutting the hairs at any desired length.

20 Thus as the clippers are moved upwardly, they may be rocked gradually so as to give the proper trim.

Another very important object of the invention resides in the production of an attachment of this nature which is capable of being held on the electro-magnetically operated clippers without independent fastening means.

A still further important object of the invention is to provide an attachment of this nature, that is exceedingly simple in its construction, strong, durable, easy to attach and detach, inexpensive to manufacture, thoroughly reliable and efficient in use, and 25 otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:

45 Figure 1 is an elevation of a well known type of magnetically driven hair clipper showing my attachment associated therewith,

Fig. 2 is a bottom plan view of the attachment on the guard plate of the clippers,

Fig. 3 is a transverse section therethrough, and

Fig. 4 is a perspective view of the attachment.

55 Referring to the drawing in detail, it will be seen that the letter C designates generally

a well known type of electro-magnetically driven hair clipper including among other elements, a guard plate G having the shoulder S and teeth T.

Referring now in detail to my attachment, it will be seen that the same is preferably constructed of resilient sheet metal and is formed in a one piece integral structure. This attachment includes a rectangular body plate 5 merging at one longitudinal edge into a body 6 of a comb which comprises the curved teeth 7 and 8, the latter of which are disposed at the end of the body 6 and have their terminals curved over upon themselves as at 9 to form hooks.

The transverse sides of the body 5 merge into rising ends 10 which are slotted as at 11 to form a tongue 12 which is curved to hook over the side edges of the guard plate 75 G. The other longitudinal side edge of the body 5 has rising from an intermediate portion thereof a lug 12 for engagement with the shoulder S. It is to be noted that in slipping this attachment over the guard 80 plate G, that the hooks 9 engage the end piece P, the lug 12, the shoulder S, and the tongues 12, the sides of the edges of the guard G. Thus the attachment is firmly 85 held in place on the guard plate against accidental displacement and against vibration.

In these electro-magnetically driven hair clippers, considerable vibration is set up because of the armature striking against the magnet. With this end in view, I construct this attachment of very light material, and thus prevent hammering. The spring nature of the attachment also aids in preventing this hammering, owing to the tight engagement caused by the gripping action when the hooks 9 are disposed over the teeth T and the lug 12 is engaged over the shoulder S and the tongues 12' are engaged over the side edges of the guard G.

When the attachment is disposed on the clippers, it will be seen that the curved teeth 8 and 7 allow the plate to be rocked on the neck, nape of the head and sides thereof so that the barber may regulate them from start to finish so that the length of the hairs may be gradually increased as the clippers move upwardly, thereby eliminating the necessity of finishing up with hand clippers.

The present embodiment of the invention has been disclosed in detail, since in actual

practice, it attains the features of advantage 5 enumerated as desirable in the statement of the invention and the above description. It will be apparent that changes in the details of construction, and in the combination and arrangement of parts may be resorted to without departing from the spirit or scope of the invention as hereinafter claimed, or sacrificing any of its advantages.

Having thus described my invention, what I claim as new is:—

1. An attachment of the class described including a substantially rectangular body 15 of resilient material in the nature of a plate, having one longitudinal edge merging into a comb body from which project curved teeth, the end teeth terminating in overhanging hooked extensions, a lug integrally

rising from the other longitudinal edge of 20 the first body, ends rising from the transverse edges of the first body and having curved tongue portions.

2. An attachment of the class described formed from resilient sheet material cut 25 and bent to provide a substantially rectangular body having one longitudinal edge merging into a comb body from which project curved teeth, the end teeth terminating in overhanging hooked extensions, a lug 30 rising from the other longitudinal edge of the first body, ends rising from the transverse edges of the first body and having intermediate portions thereof forming curved tongue portions. 35

In testimony whereof I affix my signature.

HECTOR F. PATENAUME.
